UNITED STATES PATENT OFFICE.

JOHN EVANS, OF TORONTO, OHIO, ASSIGNOR OF ONE-THIRD TO CLYDE H. CARROLL,
OF MARTINS FERRY, OHIO.

TIN-SHEET SEPARATOR.

Application filed October 3, 1921. Serial No. 505,086.

To all whom it may concern:

Be it known that I, JOHN EVANS, a citizen of the United States, residing at Toronto, in the county of Jefferson and State of Ohio, have invented new and useful Improvements in Tin-Sheet Separators, of which the following is a specification.

This invention relates to an apparatus for separating sheets of metal when the same have become stuck together, an object of the invention being to provide smooth separating rolls and corrugated gripping rolls for drawing the sheets over the separating rolls.

Another object of the invention is to provide a set of smooth rolls through which the sheets are fed after passing between the gripping rolls for rolling out the corrugations formed in the sheets by said gripping rolls.

A further object of the invention is to provide means whereby the upper and lower spaces between the gripping rolls may be adjusted independently of each other to conform to the thicknesses of the sheets passing through said spaces.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is an elevation, partly in section of the invention.

Figure 2 is an elevation of the opposite side.

Figure 3 is a section on line 3—3 of Figure 1.

Figure 4 is a longitudinal sectional view.

Figure 5 is a sectional detail view.

In these views 1 and 2 indicate the supporting frames of the apparatus, each of which being provided with the vertically extending recesses 3 for receiving the bearing blocks for the rolls. The upper end of said recesses are closed by the top plate 4 which is held to the frame by the bolts 5, said bolts being held in place by the pins 6. The bearing blocks are shown at 7.

I provide a pair of separating rolls 8 which are of smooth contour and a pair of small corrugated gripping rolls 9 and another pair of gripping rolls 10 which are also corrugated and are of considerable larger diameter than the rolls 9. The gripping rolls 9 and 10 are placed in a vertical row with the small rolls 9 intermediate the large rolls, the bottom roll 10 contacting with the lower roll 9 and the top roll 10 contacting with the upper roll 9, the two rolls 9 also contacting with each other. Said rolls 9 are also in the same horizontal planes with the smooth rolls 8. The rolls 8 and 9 are supported by the same bearing blocks, two sets of three blocks each being provided for facilitating the placing of the rolls in position. The bottom block rests upon shoulders formed in each supporting frame and the blocks are held against movement by the screws 11 which pass through the plates 4 and have their lower ends bearing against the upper block. The lower blocks 7' which support the bottom roll 10 are vertically movable by means of the screw shafts 12 engaging screw threaded sockets in the blocks and said shafts are connected by the gears 13 with the wrench receiving shaft 14. The bottom blocks of the sets of the intermediate rolls are recessed, as at 15, permitting movement of the blocks 7'. The top roll 10 is supported by the sets of blocks for the intermediate rolls and is held in place by the top block 7'' which is held in place by the screws 11' which are carried by the plates 4. The screws 11 and 11' are provided with wrench receiving heads so that they can be adjusted by a wrench.

In rear of the rolls just described are the smoothing rolls 15 which are of larger diameter than any of the rolls before mentioned and are journaled in the blocks 7'' which are held in position by the screws 11'.

The sheets to be separated are placed over the separating rolls 8 and the end of the upper plate is passed between the upper set of rolls 9 and 10 and the end of the lower plate, or plates, passed between the lower set of rolls 9 and 10. The corrugated rolls will grip the sheets and cause them to pass between the rolls, thus pulling them over the smoothing rolls 8 which will separate the plates. As the plates pass between the corrugated rolls they will be brought together.

again owing to the different sizes of the corrugated rolls, so that they will be directed between the smoothing rolls 15. These rolls 15 will take out the corrugations made in the plates by the corrugated rolls.

If more than two sheets are to be separated the top sheet is passed between the upper corrugated rolls and the space between the lower corrugated rolls is increased to 10 permit the passage of the remaining sheets. After the first sheet has been separated the remaining sheets are passed through, the second sheet being placed between the upper corrugated roll and this action is kept up 15 until all the sheets are separated. However, the corrugated rolls have a tendency to separate the sheets, if they are not too firmly connected together, so that in passing the sheets through the lower corrugated rolls 20 they may be separated and it will not be necessary to run the group of plates through the corrugated rolls again.

It will be seen that the upper and lower rolls 10 can be adjusted independently so as 25 to make the space between them and the intermediate rolls of the proper size to receive the sheets.

The lower roll 10 is connected by the gears 16 with the intermediate roll 9 which contacts therewith and this roll 9 is connected by the gears 17 with the upper roll 8. These gears are located at one side of the apparatus and at the opposite side a similar 30 arrangement of gears is provided for connecting the upper roll 10 with its contacting roll 9 and this roll 9 with the lower roll 8. Power may be applied to the large rolls 10 in any desired manner.

It is thought from the foregoing description 40 that the advantages and novel features of my invention will be readily apparent.

I desire it to be understood that I may make changes in the construction and in the combination and arrangement of the several 45 parts, provided that such changes fall within the scope of the appended claims.

What I claim is:—

1. An apparatus of the class described comprising opening rolls, gripping rolls for

feeding the sheets over the opening rolls and means for adjusting the gripping rolls in relation to each other. 50

2. An apparatus of the class described comprising smooth opening rolls, and corrugated gripping rolls for pulling the sheets 55 over the opening rolls.

3. An apparatus of the class described comprising smooth opening rolls, corrugated gripping rolls for pulling the sheets 60 over the opening rolls and means for adjusting the gripping rolls in relation to each other.

4. An apparatus of the class described comprising a pair of smooth opening rolls arranged one above the other, two pairs of gripping rolls, said gripping rolls being arranged to pull a sheet downwardly over one opening roll and upwardly over the other opening roll, said gripping rolls being corrugated. 65

5. An apparatus of the class described comprising a pair of smooth opening rolls arranged one above the other, two pairs of corrugated gripping rolls, said gripping rolls being arranged in a vertical row and the upper and lower rolls being of larger 70 diameter than the intermediate rolls and a pair of smoothing rolls for receiving the plates or sheets from the corrugated rolls. 75

6. An apparatus of the class described comprising a pair of opening rolls, two pairs of corrugated gripping rolls for pulling the sheets over the opening rolls, and means for adjusting the outer rolls of each 80 pair of gripping rolls in relation to the intermediate rolls. 85

7. An apparatus of the class described comprising a pair of side frames, bearing blocks removably carried thereby, a pair of opening rolls and two pairs of corrugated gripping rolls carried by opposing sets of said blocks, a pair of smoothing rolls carried by another set of opposing blocks and means for rotating the opening and corrugated rolls. 90 95

In testimony whereof I affix my signature.

JOHN EVANS.
